[57] CLAIM

I claim the ornamental design for a hand shield, as shown and described.

DESCRIPTION

FIG. 1 is a plan view of a hand shield showing my design;

FIG. 2 is a bottom view thereof;

FIG. 3 is a side view, the opposite side being a mirror image

thereof;

FIG. 4 is a left view thereof;

FIG. 5 is a right end perspective view thereof; and,

FIG. 6 is a side view thereof showing the hand shield with environmental structure, the environmental structure being shown in broken line fashion in FIG. 6.
